To all whom it may concern:

Be it known that I, WEBSTER TILTON, a citizen of the United States of America, residing in the county of St. Louis, in the State of Missouri, have invented a new, original, and ornamental Design for Motor-Car Bodies, of which the following is a specification, reference being had to the accompanying drawing, forming a part thereof.

The drawing discloses in Fig. 1 a side elevational view of a motor car body embodying

the new design and in Fig. 2 a plan view of a motor car body of the same design as that shown in the side elevational view.

The characteristic feature of my design is regarded as the two tone color effect embodied in the stripes above and below the door, as shown in Fig. 1.

I claim:

The ornamental design for a motor car body, as shown and described.
